UNITED STATES PATENT OFFICE.

JOSÉ FERRER AND ELIAS ALONSO, OF SAN JUAN, PORTO RICO.

REVERSING-GEAR.

1,160,058.

Specification of Letters Patent.

Patented Nov. 9, 1915.

Application filed August 8, 1914. Serial No. 855,896.

To all whom it may concern:

Be it known that we, JOSÉ FERRER, an American citizen, and ELIAS ALONSO, a citizen of Cuba, and residents of San Juan, in the District of San Juan and Island of Porto Rico, have invented certain new and useful Improvements in Reversing-Gears, of which the following is a specification.

Our invention relates to steam engines, particularly to engines provided with rotary valves for the steam inlet and exhaust, and the main object thereof is to provide means for reversing the engines.

A further object is to provide means for reversing the engine while in operation.

A further object is to accomplish this by changing the relationship of the rotary valve with respect to the crank-shaft of the engine.

A further object is to provide manual means for such reversing which are normally locked against movement.

A further object is to accomplish this result by means of a train of gears and a sectional shaft for valve rotation; and further objects are to provide such reversing means which are readily operable, simple in operation, construction, and installation, so formed as not to easily get out of order to require repair, and which are comparatively inexpensive.

Our invention is fully described in the following specification, of which the accompanying drawings form a part, in which the same reference characters are used to designate the same parts in each of the views, and in which:

Figure 1 is a central, longitudinal, horizontal, section taken through a steam engine provided with a present preferred form of our invention; Fig. 2 is an enlarged section taken on the line 2—2 of Fig. 1; Fig. 3 is a section taken on the line 3—3 of Fig. 2, of fragmentary form; Fig. 4 is a face view of the valve which we use; Fig. 5 is an enlarged, central, longitudinal, section taken on the line 5—5 of Fig. 1; Fig. 6 is a section taken on the line 6—6 of Fig. 5; and Figs. 7 and 8 are views of a detail of the valve-shaft construction.

In the drawings forming a part of this application we have shown a cylinder *a* of a steam engine of reciprocating type, provided with ports *a*² and *a*³, a piston *a*⁴, a rod *a*⁵ therefor, a connecting rod *a*⁶, and a crank-shaft *a*⁷, all of the usual or any desired con-

struction, and we provide a steam-chest *b* at one side of said cylinder.

The chest *b* consists of a cylindrical member *b*² having removable ends *b*³ and *b*⁴, the contacting surfaces of which, and of the cylindrical member *b*², being ground to provide a steamtight joint, and the member *b*² is provided with a branched steam inlet port *b*⁵ and with a branched exhaust port *b*⁶, the branches of which, as shown in Fig. 3, communicate with recesses *b*⁷ and *b*⁸ of the ends *b*³ and *b*⁴, respectively, said ends being also provided with a passage *b*⁹, each, in register with the cylinder ports *a*² and *a*³, as clearly shown in Fig. 1.

Rotatable in the steam-chest *b* is a longitudinally arranged valve-shaft *c* which is preferably transversely and angularly formed at its outer end, as shown at *c*², Figs. 5, 7 and 8, to fit into a similarly recessed coupling *c*³ keyed to a short shaft *c*⁴ rotatable in bearings *c*⁵, and to which, in turn, is keyed a casing *c*⁶ provided with an internal gear *c*⁷ and a cover *c*⁸ revolvable with the shaft *c*.

Keyed on the valve-shaft *c* are two oppositely arranged valves *d* and *e*, spaced apart in the center of the steam-chest and similarly inclined on adjacent faces for a wedge *f* arranged therebetween, and movable against inclined planes by means of a spring *f*², and the object of which is to force the said valves apart, when worn at their ends, to compensate for such wear automatically, and in no way interfering with the functions of the valves but, instead, assisting the same.

The valve *d* comprises a disk *d*² having a recess *d*³ in the outer face thereof, as clearly shown in Fig. 4, of an arc of a circle exceeding 120 degrees for a concentric portion the radius of which equals the radius of the arc on which the passage *b*⁹ of the end *b*³ is struck, whereby said recess will register with said passage for a corresponding degree of valve revolution, and said valve is also provided with a concentric slot *d*⁴, diametrically opposite the concentric portion of the recess *d*³, entirely through the disk *d*² and of the same radius as the passage *b*⁹ referred to, and of an arc exceeding 120 degrees of a circle, whereby said slot will register with said passage for a corresponding degree of valve revolution, said slot communicating with the interior of the steam-chest, and it will thus be seen that the recess *d*³ and slot *d*⁴ are al-

ternately carried into register with the said passage and thus into communication with the interior of the cylinder a , in each valve revolution, to admit steam to said cylinder 5 when said slot is in communication therewith, and to exhaust the expanded steam when said recess is in communication therewith.

The valve e is in all respects similar to the 10 valve d , having the disk e^2 , recess e^3 , and slot e^4 adapted, each, to register with the passage b^9 of the end b^4 , alternately, and thus adapted to exhaust or admit steam from and to said cylinder on the opposite side 15 of the piston a^4 from that in communication with the valve d , and it will be noted that the slots d^4 and e^4 are oppositely arranged whereby one slot and one recess of the two valves are in register at one time with the 20 corresponding passages b^9 , or vice-versa.

By reference to Figs. 5 and 6, it will be seen that the casing c^6 supports one end of a gear-shaft h provided with a bevel pinion h^2 at its opposite end enmeshed with a similar pinion h^3 on the crank-shaft a^7 , and whereby said gear-shaft h is rotated, and said gear-shaft also carries, within the casing c^6 , an integral disk h^4 having stub-shafts h^5 secured therein and diametrically opposite each other, and serving as supports for freely revoluble spur pinions h^6 which are in mesh with the internal gear c^7 of the casing c^6 and, by reference to Fig. 5, it will be seen that we provide a ring h^7 connected 30 with the stub-shafts h^5 by means of screws h^8 to maintain said stub-shafts and spur pinions in stability.

Projecting through the cover c^8 of the casing c^6 is a sleeve i revoluble therein and 40 on the gear-shaft h , as also in the support i^2 , said sleeve carrying a spur gear i^3 at its inner end in mesh with the pinions h^6 , a planetary gear thus resulting, and a hand-wheel i^4 is provided at the outer end of said 45 sleeve, preferably by means of a ratchet and pawl connection with a plate i^5 secured to the bearing support i^2 , as shown at i^6 , the details of this feature not being illustrated as any suitable form or equivalent may be 50 employed to hold the hand-wheel against movement with the gear-shaft h , but said hand-wheel is manually revoluble in a direction opposite to that of the said shaft, for reversing the valve positions from those 55 previously occupied, to reverse the engine.

The operation is very simple: The steam enters the inlet port b^5 , passes thence to the left end of the cylinder a through slot d^4 , passage b^9 , and port a^2 , and the piston is forced outwardly, actuating the crank-shaft a^7 through an arc of 180 degrees, and thereby rotating the gear-shaft h the same degree, by means of the bevel pinions h^2 and h^3 ; the shaft h revolves the casing c^6 , through 60 the medium of the internal gear c^7 and the

rotatable pinions h^6 in mesh therewith and with the normally stationary pinion i^3 , it being our intention to provide a pinion relationship insuring a full casing c^6 revolution to a full rotation of the gear-shaft h , thus 70 rotating the shafts c^4 and c at the same speed as the shaft h and thus of the crank-shaft a^7 , and, in a full outward piston movement, the valves d and e are turned through an arc of 180 degrees, whereby steam now 75 enters the cylinder through the slot e^4 and the piston returns to the initial position shown. In the forward piston movement the air, at first, and expanded steam is forced through the port a^3 , passage b^9 , and 80 recess e^3 to the corresponding branch of the exhaust port b^6 , outwardly of the engine, and in the opposite piston movement, the steam is exhausted through port a^2 , passage b^9 , recess d^3 and port b^6 , and the live steam 85 is therefore admitted to the cylinder at each cylinder end alternately, and the expanded steam exhausted from the opposite ends alternately.

If it is desired to reverse the engine, 90 whether at rest or running, all that is necessary is to revolve the hand-wheel i^4 , in a direction opposite the shaft rotation, through an arc of 180 degrees of a circle with respect to the shaft h , thus carrying 95 the pinions h^6 around on their shafts, thus revolving the casing through the medium of the internal gear c^7 and, thereby the shaft c^4 , shaft c , and connected valves d and e through an arc of 180 degrees, and the admission and exhausting of steam to the cylinder is changed to the opposite ends thereof 100 and the engine is reversed. It will thus be seen that by merely revolving the hand-wheel i^4 to change the relationship between 105 the gear-shaft h and the sleeve i the steam is directed into the cylinder end opposite to the end thereof receiving steam just before making said change, and the engine is reversed, the change in relationship being 180 110 degrees of a circle in the form shown, and this change may be made as often as desired, the hand-wheel being always revolved in the same direction for such changes, because of the hand-wheel retaining ratchet and 115 pawl arrangement, or equivalent, and such changes may be made with the gear-shaft rotating, as will be seen.

Our invention is simple in construction, 120 installation, and operation, fully efficient, and comparatively inexpensive, and various changes over the form shown and described may be made, within the scope of the following claims, without departing from the spirit of our invention or sacrificing its advantages.

Having fully described our invention, what we claim as new, and desire to secure by Letters Patent, is:—

1. In an engine, a rotary valve, a shaft in 125

operative connection therewith, a casing having an internal gear fixed on said shaft, a supplemental shaft, a plurality of gears thereon in mesh with said internal gear, a normally fixed gear in mesh with said last named gears, means for rotating said supplemental shaft to transmit motion to said first named shaft through said gears, and manual means for revolving said normally fixed gear to change the relationship of said shafts to reverse said engine.

2. In an engine, a rotary valve, a shaft in operative connection therewith, an internal gear carried thereby, a supplemental shaft, a plurality of gears carried thereby and in mesh with said internal gear, a sleeve on said supplemental shaft, a fixed gear there-

on in mesh with said last named gears, means for locking said sleeve against movement, manual means for revolving said sleeve to change the relationship of said shafts, and means for rotating said supplemental shaft to transmit motion to said first named shaft through the medium of said gears.
